UNITED STATES PATENT OFFICE.

PHILIP W. WILEY, OF WASHINGTON, DISTRICT OF COLUMBIA.

TYMPAN-GAGE ADJUSTING AND SQUARING DEVICE FOR PRINTING-PRESSES.

SPECIFICATION forming part of Letters Patent No. 726,128, dated April 21, 1903.

Application filed November 20, 1902. Serial No. 132,159. (No model.)

To all whom it may concern:

Be it known that I, PHILIP W. WILEY, a citizen of the United States, residing at Washington, District of Columbia, have invented 5 certain new and useful Improvements in Tympan-Gage Adjusting and Squaring Devices for Printing-Presses; and I do hereby declare the following to be a full, clear, and exact description of the invention, such as will enable 10 others skilled in the art to which it appertains to make and use the same.

This invention relates to means for enabling the tympan-gages of printing-presses to be set square with the form at the proper 15 distance to give the desired margins. Heretofore the current practice has been after the form has been locked in the chase and the latter secured in the bed of the press to take an impression on the tympan, which has been 20 secured by clamps over the platen of the press, and then by the eye and by measurement with an ordinary ruler from said impression to determine the places for the tympan-gages, against which each sheet of paper 25 is fed when it is placed on the platen for printing. The determination of the said places in this old way requires considerable care—more, in fact, than many printers are disposed to take, and the result is, first, a liability for the matter to be printed more or 30 less obliquely on the paper instead of square with the edges; second, a liability for the matter to be printed with a greater or a less margin than desired, and, third, a considerable 35 expenditure of time if sufficient care be taken to insure accuracy as to squareness of the printing and to size of margin.

By means of the present invention the proper places for the tympan-gages can be 40 determined with greater accuracy and facility than by the current practice or by any mode heretofore devised, so far as I am aware. The cost, moreover, of the necessary device (forming part of the invention) is trifling. 45 The invention, as well as the best mode of carrying it into effect, can most conveniently be described with the aid of the accompanying drawings, which form part of this specification.

50 Figures 1 and 2 are plan views of the platen and accessories, illustrating the two stages of setting the tympan-gages in accordance with

the invention; and Fig. 3 is a plan of another form of the new or improved adjusting and squaring device.

The platen *a* is covered with the tympan *b*, of paper or other yielding material. This tympan may be secured by clamps *c* and receives an impression of the form. Such impression may be of any desired matter; but 60 it consists as shown of the inventor's name and residence—as in printing letter-heads or envelopes, for example. So far the procedure in using my invention is the same as in the current practice.

The next operation is to determine the places for the tympan-gages *d*, Fig. 2, against which the sheets (envelops, letter-paper, or as the case may be) are fed preparatory to being carried with the platen *a* for printing 70 thereon. For effecting this a sheet *e* of transparent material, most advantageously a tough transparent material like transparent celluloid, is provided, with the two gage edges—that is to say, the two adjacent edges which 75

are to determine the positions of the tympan-gages—at right angles to each other and with two sets of gage-lines parallel to said edges, respectively. When this sheet *e* is placed over the impression on the tympan, such impression is visible through the sheet, and it is easy so to adjust the latter as that one set of 80 gage-lines thereon shall be parallel with the lines of printing and that the gage edges of the sheet shall lie beyond the impression the 85 distance desired for the respective margins in printing. Having thus placed the sheet *e* in position, lines *f*, Fig. 2, may be drawn on the tympan along the gage edges, and the sheet *e* being then removed the tympan-gages *d* can be set readily so as accurately to 90

register with lines *f*. As the gage edges of the sheet *e* are accurately squared, the lines *f* will lie strictly at right angles, and as the gages *d* are set by lines *f* the sheets fed against 95 them for printing will be accurately squared.

Any known or suitable form of tympan-gages can be used, and they may be set directly by the gage edges of the sheet *e*, although it is considered better to draw lines *f* on the tympan by said edges and to adjust the gages by such tympan-lines. Most advantageously the lines on the sheet *e* lie at such short distance apart as that when the sheet *e* is placed over 100

the impression on the tympan one or more of the said lines will fall within the impression and that the lines will form measures to aid in giving the desired margins. A proper 5 space between the lines is that of an em pica, (one-sixth of an inch,) and it is designed to use such space; but other greater or less spaces can be used.

Two sets of lines are provided on the gage 10 adjusting and squaring sheet *e*, because forms do not always have their lines of printing run in the same direction. Sometimes they run at right angles to the direction of those on the drawings, and therefore the pressman 15 would sometimes bring one set of gage-lines and sometimes the other set into parallelism with the printing-lines of the impression on the tympan, according to the disposition of the form in the bed of the press. By turning 20 the sheet *e* over, however, and a quarter of the way around the same gage edges can be used and the one set of gage-lines can be brought into parallelism with the lines of printing, whichever way these may run on the 25 tympan. In specifying, therefore, in the hereinafter-written claims that the gage adjusting and squaring sheet is provided with lines parallel with the gage edges parallelism with one or both such edges is intended. The form 30 with two sets of lines is considered, however, the best and a special improvement, because the sheet could then be used always in the same relative position on the tympan and also because the second set of lines would 35 serve as measures for securing quickly the desired distance between the ends of the lines of printing and the corresponding tympan gage or gages. The sheet *e* being loose on the tympan *b* is universally adjustable in its 40 own plane and is removable.

At *g* is an eyeleted hole for hanging up

the sheet *e*, and *h* a blank space for advertising matter. In Fig. 3 a form of sheet *e* (also within the invention) is shown, in which the back is made oblique in order to save 45 material. It would answer as well as a rectangular sheet of greater surface for most press-forms. There might, however, be some jobs wherein the margins would be so wide as to bring the impression on the tympan outside of sheet of Fig. 3, when it would not do so with a rectangular sheet, as in Fig. 1, having gage edges of the same length, respectively, as those of the sheet *e* of Fig. 3. 50

A sheet *e*, with gage edges of four and seven 55 inches, respectively, is considered to be the most useful for the general run of work; but a sheet can be used which is larger or smaller on either or on both gage edges.

I claim as my invention or discovery— 60

1. A tympan-gage adjusting and squaring device for printing-presses, consisting of a sheet of transparent material with gage edges at right angles to each other and gage-lines parallel with said edges, substantially as de- 65 scribed.

2. The combination with the platen and tympan of a printing-press, the tympan carrying the impression of the form of said press, of a universally adjustable and removable 70 tympan-gage adjusting and squaring device placed over said impression and consisting of a sheet of transparent material with gage edges at right angles to each other and gage-lines parallel with said edges, substantially 75 as described.

In testimony whereof I affix my signature in presence of two witnesses.

PHILIP W. WILEY.
